UNITED STATES PATENT OFFICE.

JOHN ASTOR VAN ALSTYNE, OF SACRAMENTO, CALIFORNIA, ASSIGNOR OF ONE-HALF
TO CASPER VINCENT SCHNEIDER, OF SACRAMENTO, CALIFORNIA.

SWITCH.

1,247,751.

Specification of Letters Patent. Patented Nov. 27, 1917.

Application filed May 5, 1917. Serial No. 166,772.

To all whom it may concern:

Be it known that I, JOHN ASTOR VAN ALSTYNE, a citizen of the United States, residing at Sacramento, in the county of Sacramento and State of California, have invented certain new and useful Improvements in Electric Switches, of which the following is a specification.

This invention relates to improvements in electric starting switches and while shown adapted to a three phase circuit is also adapted to any other phase circuit.

One of the objects of this invention is to provide a switch in which the current, supplied to a motor for instance, shall not pass through the safety fuses until the motor shall have attained its full speed, and to make possible also the use of safety fuses having an amperage more nearly corresponding to the protection desired. Under the present method of passing all the current through the fuses on starting a motor, it is necessary to provide heavier fuses so that they will not blow out but which consequently do not give the desired protection to the motor after it is running.

Another object is to provide an inclosed switch which shall automatically be thrown to open position when the cover is removed; still another object is to provide means whereby the switch may be locked in open position for protection to workmen making repairs; and further to provide means whereby the switch may be thrown open with the cover in closed position.

Various other objects and advantages will be apparent as the description progresses, and while I have illustrated what I consider the best embodiment of my invention, I do not wish thereby to limit myself thereto, as various changes within the scope and spirit of this invention may be made without sacrificing any of the numerous advantages attained thereby.

In the drawings, Figure 1 is a front elevation of the switch, the cover being removed; Fig. 2 is a partial side elevation of the switch looking to the right and showing the same in running position; Fig. 3 is the same view showing the switch in open position; Fig. 4 is a side elevation of the inclosing casing, with the switch removed, to more fully illustrate the switch handle and the means for locking the same in open position; Figs. 5 and 6 are diagrammatic

views of my invention showing one form of connections and at the same time indicating a modification of construction.

In the drawings, a suitable insulating base 1 is shown upon which are mounted the various devices described. In this instance, a jointed double-connection three-pole switch is illustrated comprising blade members 2-3, 4-5 and 6-7 which are hinged at their inner ends and revolvably mounted in standards 8, 9 and 10. The upper ends of the blade members 3, 5 and 7 form contacts with the standards 11, 12 and 13 respectively, and the lower ends of the blade members 2, 4 and 6 form contacts with the standards 14, 15 and 16. Insulating bars 24 and 24' connect these blade members into two sections. Safety fuses 17, 18 and 19 respectively connect standards 8, 9 and 10 with contacts 14, 15 and 16. Springs 20 and 21 are provided mounted on suitable standards and which are connected at their outer ends to the upper blade members 3 and 7 for causing the upper section of the switch to be thrown outward on release of a catch to be hereinafter mentioned.

Pivotedly mounted on the lower blade member 4 is a lever 22 whose upper end passes loosely through a guide 23 mounted on the insulating bar 24. For limiting the outward movement of the upper section of the switch, a pin or lug 25 is provided on the lever 22. A fulcrum 26 is mounted on the insulating base 1 and under certain conditions acts to throw the lower section of the switch outward and away from the contacts 14, 15 and 16.

The contact standards 11, 12 and 13 are provided with means for attaching the main lead wires, while the contact standards 14, 15 and 16 have means for attaching the feed wires to the motor. Mounted on the insulating bar 24 is a notched bolt 27 held in releasable position by a keeper 28, said keeper being slidably mounted in a bracket 29 and controlled by links 30 and the lever 31. Above the lever 31 is mounted a solenoid 32, one terminal being connected to the standard 14 and the other to the standard 16. The catching device thus illustrated is covered by Letters Patent issued to me Oct. 10th, 1916, #1,201,114.

A manually operated U-shaped handle bar 33 is provided pivotally mounted in openings in the side walls 34 and 35 form-

ing part of the main frame in which the base 1 is secured; the middle portion of the U-shaped part bears against the bolt 27. The outer end of the handle is provided 5 with a staple 33' to which a padlock may be secured, and about midway between this staple and the bearing is a projecting lug 36.

With this preliminary description, the operation of my improved switch will be explained.

The switch is in open position as shown in Fig. 3 and diagrammatically as in Fig. 5, and it is desired to operate a motor (not shown) connected therewith. The handle 15 33 is thrust forward until the under surface of the lever 22 comes in contact with the fulcrum 26 when further movement is ceased. This will bring the upper blade members 3, 5 and 7 in contact with main 20 lead standards 11, 12 and 13, the lower blade members 2, 4 and 6 still remaining in contact with the standards 14, 15 and 16 connected to the motor, as shown by the dotted lines in Figs. 3 and 5. The motor will 25 then start, the current passing through the upper and lower blade members but not through the fuses. This describes the first closing movement.

As soon as the motor has attained full 30 speed, a further thrust is given the handle 33 which causes the lower end of the lever 22 to be raised thus forcing the lower blade members 2, 4 and 6 out and away from their contact standards 14, 15 and 16 as shown in 35 Figs. 2 and 6, and causing the current to pass through the fuses.

For the purpose of assisting the outward throw of the lower section of the switch, springs 37 may be provided; and for limiting the outward throw of said lower section, 40 a pin or lug 25 is provided on the lever 22. If it is desired to open the switch, a button 38 may be pressed causing a crank-lever 39 to move the releasing lever 31 which will 45 cause a disengagement of the keeper 28 from the notched bolt 27. By reason of the springs 20 and 21, the upper section of the hinged switch will be thrown forcibly outward and the lever 22 will cause the lower 50 section to be thrown downward into contact position with the standards 14, 15 and 16, the pin or lug 25 bearing against the guide 23. Should the current be disrupted by 55 reason of a main switch (other than the switch here described) being opened, or should there be a failure of current for any other cause, the armature 40 in the solenoid 32 will drop upon the releasing-lever 31 causing the switch to be opened in the same 60 manner as when pressing the button 38. Should the cover 41 of the inclosing casing 42 (Fig. 4) be removed, the switch being closed, a spring 43 will be released by the crank-lever 44 causing a downward move- 65 ment of the armature 40 against the releas-

ing-lever 31 permitting the switch to open in the same manner as when pressing the button or when the current is disrupted.

In order to prevent the switch being closed, thus endangering workmen making 70 repairs to the electrical equipment, the operating handle bar 33 may be padlocked to the bar 45 through the staple 33' and opening 46. The bar 45 is also provided with a notch 46' which of its own weight drops 75 onto the lug 36 and when the handle 33 is thrust forward said lug will come in contact with this notch and prevent further movement of the lever. This corresponds with the first closing movement previously described and is a precaution against the operator throwing the upper section of the switch into full contact thereby releasing the lower section (before the motor has attained full speed) and causing the fuses to 80 be blown. To effect the final closing movement, the bar 45 is manually displaced as indicated by the dotted line in Fig. 4 when the handle bar 33 may be further thrust forward, thus completing the second or final 85 closing movement.

Having thus described my invention, what I claim as new and desire to protect by Letters Patent, is:—

1. In a switch, in combination, one or 90 more switch blades each comprising two members pivotally joined together and pivotally connected at their hinged ends to standards mounted upon an insulating base, contact standards also mounted upon the 100 base, adapted to contact with the free ends of the blade members, and a fuse for each blade connecting the central standard to one of the outer contact standards whereby when both members of a blade are in contact positions, the fuse is shunted, when the blade member on the fused side is open the fuse will be in circuit and when the other blade member is in open position the circuit is 105 open.

2. In a switch, in combination, one or more switch blades each comprising two members pivotally joined together and pivotally connected at their hinged ends to standards mounted upon an insulating base, contact 110 standards also mounted upon the base adapted to contact with the free ends of the blade members, a fuse for each blade connecting the central standard to one of the outer contact standards, and resilient means 115 for rotating the non-fused blade-member about the fused blade member independent of the same.

3. In a knife switch, in combination, a plurality of blades arranged in two sections, 120 each blade being composed of two members pivotally joined together and pivotally connected at their hinged ends to standards mounted upon an insulating base, contact standards also mounted upon the insulating 125

base adapted to contact with the free ends of the blade members, a fuse for each blade member of the lower section connecting the central standard with its outer contact standard, and resilient means for rotating the upper blade section about said pivotal points independent of the lower section.

4. In a knife switch, in combination, a plurality of blades arranged in two sections, 10 each blade being composed of two members pivotally joined together and pivotally connected at their hinged ends to standards mounted upon an insulating base; contact standards also mounted upon the insulating 15 base adapted to contact with the free ends of the blade members; a fuse for each blade member of the lower section connecting the central standard with its outer contact standard; a fulcrum mounted upon the base; a 20 lever pivotally connected to one blade member of the lower section at an intermediate point on said blade; a guide secured to the outer end of the other blade member, said guide having a slot for loosely receiving the 25 outer end of said lever, said lever being adapted to engage the fulcrum at a predetermined point, and said lever also having near its outer end between the guide and the pivoted end of the lever a pin or lug for 30 limiting the movement of one section upon the other.

5. In a knife switch, in combination, a plurality of blades arranged in two sections, each blade being composed of two members 35 pivotally joined together and pivotally connected at their hinged ends to standards mounted upon an insulating base; contact standards also mounted upon the insulating base adapted to contact with the free ends 40 of the blade members; a fuse for each blade member of the lower section connecting the central standard with its outer contact standard; a fulcrum mounted upon the base; a lever pivotally connected to one blade 45 member of the lower section at an inter-

mediate point on said blade; a guide secured to the outer end of the other blade member, said guide having a slot for loosely receiving the outer end of said lever, said lever being adapted to engage the fulcrum at a 50 predetermined point, and said lever also having near its outer end between the guide and the pivoted end of the lever a pin or lug for limiting the movement of one section upon the other, and resilient means for rotating the upper blade section about said pivotal points independent of the lower section.

6. In a knife switch in combination, a plurality of blades arranged in two sections, each blade being composed of two members 60 pivotally joined together and pivotally connected at their hinged ends to standards mounted upon an insulating base; contact standards also mounted upon the insulating base adapted to contact with the free ends of the blade members; a fuse for each blade member of the lower section connecting the central standard with its outer contact standard; a fulcrum mounted upon the base, a lever pivotally connected to one blade member 65 of the lower section at an intermediate point on said blade; a guide secured to the outer end of the other blade member, said guide having a slot for loosely receiving the outer end of said lever, said lever being adapted 70 to engage the fulcrum at a predetermined point and said lever also having near its outer end between the guide and the pivoted end of the lever a pin or lug for limiting the movement of one section upon the other; 75 resilient means for rotating the upper blade section about said pivotal points independent of the lower section; and a latch-bolt mounted on the upper blade section adapted to engage a solenoid-controlled 80 catch mechanism.
